UNITED STATES PATENT OFFICE.

JAMES C. WOODSON, OF MANSFIELD, OHIO, ASSIGNOR TO WESTINGHOUSE ELECTRIC PRODUCTS COMPANY, A CORPORATION OF MICHIGAN.

DESIGN FOR AN AUTOMATIC ELECTRIC BAKE OVEN.

60,186.

Specification for Design.

Patented Jan. 3, 1922.

Application filed June 3, 1921. Serial No. 474,775. Term of patent 7 years.

To all whom it may concern:

Be it known that I, JAMES C. WOODSON, a citizen of the United States of America, residing at Mansfield, in the county of Richland and State of Ohio, have invented a certain new, original, and ornamental Design for Automatic Electric Bake Ovens, of which the following is a specification, reference being had to the accompanying drawing, forming a part hereof.

The single figure of the drawing is a view,

in perspective, of an automatic electric bake oven, embodying my new design.

I claim:

The ornamental design for an automatic electric bake oven substantially as shown and described.

In testimony whereof I have hereunto subscribed my name this 23rd day of May, 1921.

JAMES C. WOODSON.
